DISPOSABLE ASH RECEIVING RECEPTACLE Augusta K. Brumby, Coral Gables, and Anne B. Mergen,
Miami, Fla.

Application August 16, 1955, Serial No. 528,740

5 Claims. (Cl. 229—1.5)

This invention relates generally to a disposable ash receiving receptacle. More specifically, the invention is directed to an ash receiving receptacle having a collapsible pocket formed of a semi-flexible fire-resistant material such as metal foil which has sufficient rigidity to be self-supporting so that such pocket will tend to remain closed in its collapsed state and remain open for use when opened by an intended user. Further, the invention is directed to a disposable ash receiving receptacle including a collapsible pocket formed of a material as described above and secured to a sheet of absorbent material which may be engaged with the exterior surface of a drinking glass to support the pocket on such glass and absorb moisture which collects on the exterior of such glass.

At social gatherings it very often is impractical to provide separate ash trays for the guests present to dispose of ashes from their cigarettes and cigars, as well as cigarette and cigar butts. Such problem becomes particularly acute in instances where groups at a party tend to congregate while standing, finding it necessary to have at hand an ash tray for disposal of ashes from their cigarettes or cigars. The situation is additionally complicated by having to hold a glass containing a beverage refreshment in addition to the ash tray.

The impracticality of providing individual ash trays of the more conventional type for each guest and the inconvenience to the guest in having to keep such ash tray immediately at hand, has given rise to the need for a disposable ash tray which may be produced at a relatively low cost so that each guest who is inclined to smoke may be provided with a means of disposal of ashes, etc. To alleviate the necessity for handling a separate article in addition to the drinking glass which the guest has, it is desirable that the disposable ash receiving receptacle be adapted to be conveniently associated with such drinking glass so that an ash receptacle is readily available, positioned on the side of the drinking glass for use as the need arises. Such positioning of the ash receptacle necessitates a construction wherein the beverage contained in the drinking glass may be consumed without the unintentional emptying of the ash receptacle.

To overcome the problems as outlined hereinabove, it is a principal object of the instant invention to provide a disposable ash receiving receptacle including a collapsible pocket, which pocket is characterized by having sufficient rigidity in walls thereof to retain the pocket open for reception of cigarette and cigar ashes, etc., or closed to retain such ashes for ready disposal.

It is another object of this invention to provide a sheet of material having a collapsible pocket carried thereby with such pocket having walls constructed of semi-flexible fire-resistant material possessing sufficient rigidity to retain

2

the mouth of said pocket closed when the pocket is collapsed and holding the mouth open when the pocket is opened by the intended user, and which sheet of material is adapted to be engaged with the exterior of a drinking glass to position the pocket with respect to such glass for use as an ash disposal receptacle.

It is a further object of this invention to provide a disposable ash receiving receptacle having a sheet of absorbent material with an ash receiving pocket carried thereby, wherein said pocket has walls constructed of a semi-flexible fire-resistant material possessing sufficient rigidity to retain the mouth of the pocket closed when such pocket is collapsed, and open when the pocket is opened by the intended user.

It is also an object of this invention to provide a disposable ash receiving receptacle including a sheet of absorbent material with a sheet of semi-flexible fire-resistant material secured thereto with the latter sheet having overlapping folds closed at one end to form a pocket open at the opposite end and wherein said pocket has folds made of a material such as metal foil which is self-supporting and will retain the pocket open to receive ashes, etc., or closed to retain such ashes for disposal.

The above and other more specific objects of the instant invention will be apparent by reference to the hereinafter set forth description of an embodiment of the invention as illustrated on the accompanying drawing. It will be recognized that within the scope of the appended claims, the invention may be incorporated into a wide variety of different constructions other than that specifically illustrated on the drawing.

In the drawings:

Figure 1 is a perspective view showing the disposable ash receiving receptacle of the instant invention positioned on the exterior of a drinking glass;

Figure 2 is a sectional view taken on line 2—2 of Figure 1;

Figure 3 is an elevational view of the disposable ash receiving receptacle;

Figure 4 is a sectional view taken on line 4—4 of Figure 3; and

Figure 5 is a sectional view taken on line 5—5 of Figure 3.

Referring to Figures 1 and 2 of the drawing, there is shown thereon a more or less conventional drinking glass 10, having the disposable ash receiving receptacle of the instant invention positioned thereon. The disposable receptacle includes a sheet of material in the form of an elongated strip 12 which in being engaged with glass 10 is wrapped around the glass so that the ends overlap, as shown at 13 on Figure 2.

Disposed intermediate the ends of elongated strip 12, and preferably nearer one end of such strip, there is provided a collapsible pocket 14. This pocket is constructed of a semi-flexible fire-resistant material such as metal foil which possesses sufficient rigidity so as to be, in effect, self-supporting. Thus, the pocket, by reason of the nature of the material of which it is constructed, will tend to remain open once opened by an intended user for disposal of ashes, etc., and likewise when collapsed by the user will remain closed to retain the ashes which have been dispensed thereinto. Although metal foil has been found to be ideally suited for use in construction of pocket 14, since it possesses both the necessary fire-resistant and semi-flexible characteristics required for the pocket, it will be recognized that within the scope of this invention

other materials may be employed which possess these desired characteristics.

In the embodiment illustrated on the drawing, the elongated strip 12 includes an inner sheet of absorbent material 15 such as paper, united with an outer sheet of material 16. Such outer sheet, in the illustrated form, is folded to form collapsible pocket 14. The sheet of absorbent material 15 and outer sheet 16 are united as shown more clearly in Figure 5 by being interfolded at 17 and 18 to form seams extending longitudinally of the top and bottom of such sheets.

As shown, the outer sheet 16 is of the material which is used in formation of pocket 14. In forming the pocket 14, sheet 16 is folded at 20, 21, 22 and 23 to form a pair of overlapping folds so that the crease at 20 overlies the crease at 23 and vice versa. The overlapping folds thus function as the inner wall of pocket 14, whereas the portion 24 intermediate the creases at 21 and 22 serves as the outer wall of such pocket. To complete the bottom of the pocket, the overlapping folds are folded at one edge of sheet 16 into seam 18. Such closing of one end of the overlapping portions forms the bottom of pocket 14, whereas the opposite end remains open so that the pocket may be opened to the position as shown more clearly in Figures 1 and 2, and also in phantom view in Figure 4.

In use, the device of the instant invention is adapted to be positioned on a drinking glass as shown in Figures 1 and 2, so that the sheet of absorbent material 15 is in direct contact with the glass, and functions as a coaster or "soaker," absorbing moisture which collects on the exterior of the glass. Such positioning of the device on a drinking glass also properly locates pocket 14, so that the elongated mouth thereof faces upwardly. Thus by grasping portion 24 of the pocket, the pocket may be opened to receive ashes, etc., which are to be discharged therewith.

While the glass is being held upright, the person holding such glass retains the disposable ash receiving receptacle of the instant invention on the glass, much in the manner as a napkin may be employed to absorb moisture which tends to condense on the exterior of a glass containing a chilled beverage. At such times as the contents of the glass are to be consumed, the pocket 14 is collapsed by merely applying pressure to the portion 24 thereof, so that any ashes in such pocket will be retained without spilling during tipping to consume the beverage in the glass. Further, pocket 14 provides an effective place for disposal and extinguishing of cigarette butts, since by merely closing the pocket with the butt contained therein, air is cut off and the cigarette is rapidly extinguished. In view of the inexpensive construction of the disposable ash receiving receptacle of the instant invention, the entire device may be discarded when it has served its function and a new device substituted.

In the embodiment illustrated on the drawing, only a single specific construction has been shown. It will be readily recognized that within the scope of the instant invention, a wide variety of modifications may be incorporated without departing from the spirit of this invention. If desired, the sheets 15 and 16 need not be interfolded to form seams 17 and 18, although by such interfolding the upper seam 17 does facilitate grasping of the upper lip of pocket 14 to open the pocket for use. Instead, the two sheets may be cemented or otherwise secured together. In such case, the bottom of the pocket could be closed by cementing the overlapping folds. Also a particular form of pocket has been shown on the drawing with the pocket having a generally rectangular configuration. The pocket may be other than rectangular in shape, as long as it is secured to the sheet of material which supports it on the drinking glass, in such a manner that the pocket may be readily opened and closed, with the material of the walls of the pocket functioning to retain the pocket

opened or closed, depending upon the state to which it is moved. It may be further noted that although as shown, the entire pocket is formed of a semi-flexible fire-resistant material such as metal foil, only a portion of the pocket need be constructed of such a material as long as the pocket as a whole possesses the characteristics of being fire-resistant and self-supporting to retain the pocket opened or closed as desired by the user, without necessitating the user's holding the pocket in the desired state.

Additionally, it will be recognized that an extra portion of absorbent sheet material 15 may be provided, over and above that which backs sheet 16 as illustrated on the drawing so that such excess absorbent sheet material may hang down beneath the elongated strip 12. This excess portion of the absorbent sheet material, in use, of the device, may be tucked under the bottom of the glass to absorb moisture which collects adjacent the lower portion of the glass and thereby effectively provide a coaster for the glass.

A further advantage attributable to the disposable ash receiving receptacle of the instant invention, is the fact that the pocket thereof and the device as a whole may be folded flat. This facilitates packaging of a plurality of the devices for sale, and accordingly, reduces the expense of shipping and storing a quantity of the devices.

Having thus described our invention, what we claim is:

1. A disposable ash receiving receptacle and flexible supporting sheet therefor, comprising in combination an elongated flexible sheet of material engageable in band-like relation around the exterior curved surface of a drinking glass, a collapsible pocket on said sheet and having an elongated mouth opening toward one side edge of said sheet and upwardly when said sheet is engaged with a drinking glass with said mouth extending a distance around the circumference of the glass, said pocket having walls thereof constructed of a substantially nonresilient semi-flexible fire-resistant material which possesses sufficient self-supporting rigidity to retain the mouth of said pocket closed when the pocket is collapsed by pressing it into engagement with the curved surface of the glass on which it is carried, and hold the mouth open when the pocket is opened by the intended user.

2. A disposable ash receiving receptacle as recited in claim 1, wherein said sheet is absorbent paper to absorb moisture which collects on the exterior of a glass and said semi-flexible fire-resistant material is metal foil.

3. A disposable ash receiving receptacle and flexible supporting sheet therefor comprising in combination an elongated flexible sheet of absorbent paper engageable in band-like relation around the exterior curved surface of a drinking glass to absorb moisture which collects on the exterior of a glass, a sheet of substantially nonresilient semi-flexible fire-resistant material secured to said sheet of absorbent paper and having sufficient rigidity to be self-supporting in the absence of forces tending to bend such material, said sheet of material having a pair of overlapping folds extending transversely thereof with one end of such folds being closed to form the bottom of a pocket, said pocket opening toward one side edge of said sheet and outwardly of the end of said folds opposite said one end with the pocket mouth extending a distance around the circumference of the glass, and said folds permitting opening and collapsing of said pocket relative to said sheet of absorbent paper.

4. A disposable ash receiving receptacle as recited in claim 3, wherein said semi-flexible fire-resistant material is metal foil.

5. A disposable ash receiving receptacle and flexible supporting sheet therefor comprising in combination an elongated flexible sheet of absorbent paper engageable in band-like relation around the exterior curved surface of a drinking glass to absorb moisture which collects on the exterior of a glass, a collapsible pocket secured to said sheet adjacent the upper end of said pocket only at a

portion generally midway of the side edges of said pocket to facilitate opening and closing of said pocket while supported by said flexible sheet on the exterior curved surface of a drinking glass, said pocket having an elongated mouth opening toward one side edge of said sheet and upwardly when said sheet is engaged with a drinking glass with said mouth extending a distance around the circumference of a glass, said pocket having walls thereof constructed of a substantially nonresilient, semi-flexible, fire-resistant material which possesses sufficient self-supporting rigidity to retain the mouth of said pocket closed when the pocket is collapsed by pressing it into engagement with the curved surface of a glass on which it is carried, and hold

the mouth open when the pocket is opened by the intended user.
